UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SHADE-HOLDING DEVICE.

1,238,485.

Specification of Letters Patent. Patented Aug. 28, 1917.

Application filed November 19, 1915. Serial No. 62,424.

To all whom it may concern:

Be it known that I, REUBEN B. BENJAMIN, a citizen of the United States, residing at Chicago, in the county of Cook and State of Illinois, have invented new and useful Improvements in Shade-Holding Devices, of which the following is a full, clear, concise, and exact description, reference being had to the accompanying drawing, forming a part 10 of this specification.

My invention relates to shade holding devices.

Among the objects of my invention is to provide a shade holding device which will 15 be simple in construction and efficient in use.

In the drawings in which I have shown several embodiments of my invention—

Figure 1 is a view showing a pull switch socket in side elevation and my improved 20 shade holding device and shade in vertical section;

Fig. 2 is a section on the line 2—2 of Fig. 1;

Fig. 3 is a side elevation of the shade 25 holding device before it is connected to the shade;

Fig. 4 is a plan view of Fig. 3;

Fig. 5 is a section on the line 5—5 of Fig. 2;

Fig. 6 is a perspective view of the clamp- 30 ing band; and

Fig. 7 is a perspective view of the connecting member 17;

Fig. 8 is a vertical section of a modified 35 form of my invention;

Fig. 9 is a vertical section of still another form.

Referring now to the drawings in detail and first to the form shown in Figs. 1 to 7 40 inclusive, I have shown my invention in connection with a pull switch lamp socket 10, a shade 11, and a shade holder 12 for connecting the shade to the socket.

The socket 10 is shown as of the angle 45 type and is provided with a downwardly turned tubular member or horn 13 through which the pull chain 14 extends for operating the switch. The socket is provided with the usual bead 15 for engaging the shade holding device. The shade 11 has an opening 16 the edge of which is engaged by the connecting member 17 which carries the clamping member 18 which engages the bead 15 of the socket. The connecting member

17 comprises an annular shade engaging 55 portion 19 the lower edge of which is expanded to engage the inner surface of the shade, an annular connecting and stiffening portion 20, and a plurality of inwardly extending tongues 21 and 22 in which the 60 clamping member 18 is movably mounted. These tongues may be provided with reinforcing bosses or ribs 23. The clamping member 18 comprises a clamping ring 24 beaded outwardly at 25 to coöperate with 65 the bead 15 and ears 26 through which extends a screw 27 for clamping the band on the socket. The ring 24 is provided with openings 28 and 29 to receive the tongues 21 and 22, respectively, whereby the ring is 70 movably mounted on these tongues. These tongues 21 and 22 are turned downwardly as shown at 30 after they are inserted through the openings 28 and 29 to retain the parts in their proper position. The ring 24 is bent 75 outwardly as shown at 31 to provide a U-shaped portion which increases the springiness of the ring and also provides a passage for the pull chain 14 from the horn 13 to the space between the lamp and shade. The 80 ears 26 may be cut down as shown at 32 to provide clearance for the stem of a key operated socket in case the holder is used with a socket of this type. Portions of the ring 24 are depressed as shown at 33 be- 85 tween the openings 28 and 29 to engage the lower portion of the bead 15 on the socket.

In connecting the holder to the socket the screw 27 is backed off until the opening in the ring 24 is large enough to permit the ring 90 to be slipped over the bead 15 until the bead 25 is in proper position to engage the bead 15. The screw 27 is then tightened causing the ring to be contracted until it securely engages the socket, the ring having sufficient 95 play in the tongues 21 and 22 to permit this movement.

In Fig. 8 a modification is shown in which the clamping member 18 is supported by tongues struck up from the material of the 100 shade itself. Referring to this modification in detail the shade 34 has a plurality of tongues 35 struck up therefrom which extend through the openings 28 and 29 in the clamping member 18 and are bent downwardly as at 36 to hold the member 18 in position. The member 18 is so mounted on the tongues 35 as to have a limited move- 105

ment thereon to permit the member to be clamped around the lamp socket as in the modification of Figs. 1 to 7.

In Fig. 9 a still further modification is shown in which the shade holder 37 is detachably connected to the shade. In this modification the shade holder 37 which is made of sheet material has tongues 38 struck up therefrom which extend through openings 28 and 29 in the clamping member 18, these tongues 38 being turned downwardly as at 39 to hold the member 18 in its proper relative position. The shade holder 37 has a number of downwardly extending ears 40 through which are threaded screws 41 for engagement with the neck of the shade.

The use and operation of this modification is substantially the same as that of Fig. 8.

Having thus described my invention what I claim as new and desire to secure by Letters Patent is;—

1. In a device of the class described, a shade having an opening therein, a sheet metal member having an annular portion secured within said opening, said sheet metal member having a plurality of inwardly and radially extending tongues, and a clamping band provided with means for engaging a lamp socket, said clamping band being provided with a plurality of radially extending openings through which said tongues extend, said clamping band being slidably supported on said tongues.

2. The combination with a switch socket

provided with a pull member, of a shade holding device comprising a clamping band engaging said socket, said clamping band having a loop portion through which said pull member extends.

3. The combination with a switch socket provided with a pull member, of a shade holding device comprising a clamping band engaging said socket, said clamping band having a loop portion through which said pull member extends, and two arcuate portions connected with said loop portion for engaging said socket.

4. A shade supporting device comprising a clamping band provided with means for engaging a lamp socket, said clamping band having a radially extending opening therein and means for supporting a shade comprising a tongue extending loosely through said opening, said clamping band being slidably supported on said tongue.

5. In a device of the class described a shade of sheet material having an opening, and a plurality of tongues integral therewith and struck up therefrom adjacent said opening, and a clamping band provided with means for engaging a lamp socket, and having a plurality of radially extending openings therein through which said tongues extend loosely, said clamping band being slidably supported on said tongues.

In witness whereof, I have hereunto subscribed my name.

REUBEN B. BENJAMIN.
